Patented Mar. 9, 1971

220,113

RECORDING SYSTEM CONSOLE

Edgar F. Trombly, Grosse Pointe Farms, Mich., assignor
to Scanfax Systems Corporation, New York, N.Y.

Filed Oct. 1, 1969, Ser. No. 19,366

Term of patent 14 years

Int. Cl. D6—01

U.S. Cl. D33—19

Fig. 2

Fig. 3

Fig. 4

Fig. 5

FIG. 1 is a front perspective view of the design for a recording system console with a roll top cover for the horizontal panel thereof in retracted position;

FIG. 2 is a back elevational view thereof;

FIG. 3 is a right-side elevational view thereof;

FIG. 4 is a top plan view thereof; and

FIG. 5 is a front perspective view thereof with the roll top cover for the horizontal panel in closed position.

I claim:

The ornamental design for a recording system console, as shown and described.
